Assistant Examiner — Melvin L Davis

(74) Attorney, Agent, or Firm — Wolf, Greenfield & Sacks, P.C.

(57) **CLAIM**

The ornamental design for the dock with repositionable cushions as shown and described.

DESCRIPTION

FIG. 1 is a perspective view of the dock with repositionable cushions in accordance with our new design.

FIG. 2 is a top plan view of the dock with repositionable cushions.

FIG. 3 is a bottom plan view of the dock with repositionable cushions.

FIG. 4 is an-elevational view of the dock with repositionable cushions as see from the left side of FIG. 2., the other three side view being identical thereto; and,

FIG. 5 is a top plan view of the dock with repositionable cushions, with the cushions re-positioned to the center of the dock.

The broken line showing of the dock with repositionable cushions is for the purpose of illustrating portions of the article that form no part of the claimed design.
